UNITED STATES PATENT OFFICE.

CHARLES F. DOEBLER, OF NEW YORK, N. Y., ASSIGNOR TO NATIONAL HYDRAULIC CONSTRUCTION COMPANY, A CORPORATION OF NEW YORK.

DAM CONSTRUCTION.

1,010,735.

Specification of Letters Patent.

Patented Dec. 5, 1911.

Application filed October 11, 1910, Serial No. 586,583. Renewed October 11, 1911. Serial No. 654,250.

To all whom it may concern:

Be it known that I, CHARLES F. DOEBLER, a citizen of the United States, and a resident of New York city, in the county of 5 New York and State of New York, have invented certain new and useful Improvements in Dam Constructions, of which the following is a specification.

My invention relates to dam construction 10 and the object of my invention is to provide a hollow dam of concrete or other suitable material of like nature which can be molded, and to provide a deck which is preferably formed integral with the buttresses and 15 which is reinforced with metal rods extending longitudinally in such a manner as to form a cantaliver construction by arranging a series of upper and lower rods, one series extending from buttress to buttress within the deck and the other series 20 extending across the buttresses and above the ends of the lower rods. A further series of rods may be used extending from the bottom to the top of the deck and preferably 25 located about half way between the upper and lower surfaces of the deck and between the buttresses only, the object being to strengthen the deck to a sufficient degree to form a safe structure with as few rods as 30 possible. Corbels may be used to further strengthen and support the deck and by their use the length of the lower series of rods may be reduced.

Referring to the drawings which form a 35 part of this specification, Figure 1 is a cross sectional view of my dam taken on line $x-x$ of Fig. 3 and on a reduced scale. Fig. 2 is a plan view of a portion of the deck shown partly in section to disclose the 40 strengthening rods. Fig. 3 is a longitudinal sectional view of a portion of the dam, viewed from the down-stream side, in which the corbel construction is embodied. Fig. 4 is an exterior view of a portion of the 45 dam on a reduced scale from Fig. 3 from the down-stream side. Fig. 5 is a rear sectional view of a dam constructed without the use of corbels.

A, indicates the buttresses which extend 50 practically in alinement with the flow of the stream and may rest on a natural or

artificial foundation. In the drawings they are shown as resting directly on the earth.

A' indicate corbels which are located on each side of the buttresses at their tops, and 55 B indicates the deck which extends at an angle to the base as shown and is usually formed integral with the buttresses and corbels.

Embedded in the deck between the buttresses and extending from the bottom to the top of the dam are rods C—C—C etc., the number depending on the weight of water to be supported and the distance the buttresses are spaced apart, the proper number 65 and size being determined by an engineer in this line.

Located below the rods C—C—C etc. are cross rods D—D etc. which extend from corbel to corbel across the spaces between 70 the buttresses, and extending across the buttresses and corbels are rods E—E etc. the ends of which overlie the ends of the rods D, but are usually spaced half way between and above them as illustrated in Figs. 1 75 and 2.

In Fig. 5 the buttresses are spaced apart the same distance as shown in Fig. 3, but the corbels are omitted and therefore the lower rods are made longer to extend to or 80 nearly to the buttresses and the upper rods are also made longer to extend farther across the space between the buttresses to support the deck.

By the arrangement of the rods as above 85 described the deck will expand and contract evenly, and no portion of the deck is liable to give way under the stresses set up by the fluctuating load of water.

The general method of constructing the 90 buttresses and deck of dams of this type is known to this art and it is therefore thought to be unnecessary to further describe the present construction.

Having thus described my invention what 95 I claim as new is:

1. A hollow gravity dam embodying buttresses spaced apart from each other and a deck formed integral therewith and provided with a series of rods embedded therein 100 and extending from the bottom of the deck toward the top thereof, and a series of cross

rods embedded in the deck below said first named rods and between said buttresses, and a series of cross rods embedded in said deck and extending across said buttresses with 5 their ends above said last rods and located above said first rods.

2. A hollow gravity dam embodying buttresses spaced apart from each other and provided with corbels which extend along the top of the buttresses, and a deck formed integral therewith and provided with a series of rods embedded therein and extending from the bottom of the deck toward the top thereof, and a series of cross rods embedded in the deck below said first named rods and between said buttresses, and a series of cross rods embedded in said deck and extending across said buttresses with their ends above said last rods and located above said first rods.

3. A hollow gravity dam embodying buttresses spaced apart from each other and a deck formed integral therewith and provided with a series of rods embedded there-
25 in and extending from the bottom of the deck toward the top thereof, and a series of cross rods embedded in the deck below said first named rods and between said buttresses, and a series of cross rods embedded in said deck and extending across said buttresses with their ends above said last rods and located above said first rods, and extending over said first rods which are located adjacent to said buttresses.

35 4. A hollow gravity dam embodying buttresses spaced apart from each other and provided with corbels which extend along the top of the buttresses, and a deck formed integral therewith and provided with a
40 series of rods embedded therein and extending from the bottom of the deck toward the top thereof, and a series of cross rods embedded in the deck below said first named rods and between said buttresses, and a series
45 of cross rods embedded in said deck and extending across said buttresses and corbels, and their ends resting above the ends of said second named rods.

5. A hollow gravity dam embodying buttresses spaced apart from each other and provided with corbels which extend along the top of the buttresses, and a deck formed integral therewith and provided with a series of rods embedded therein and extending from the bottom of the deck toward the top thereof, and a series of cross rods embedded in the deck below said first named rods and between said buttresses, and a series of cross rods embedded in said deck and extending across said buttresses with their ends above said last rods and located above said first rods, and extending over the first mentioned rods which are located adjacent to said corbels.

65 6. A hollow gravity dam embodying but-

tresses spaced apart from each other and extending in a line with the stream thereby providing spaces of even distances between said buttresses, and a deck formed integral therewith and provided with a series of rods 70 embedded therein and extending from the bottom of the deck toward the top thereof, and a series of cross rods embedded in the deck below said first named rods and between said buttresses, and a series of cross 75 rods embedded in said deck and extending across said buttresses with their ends above said last rods and located above said first rods.

7. A hollow gravity dam embodying buttresses spaced apart from each other and extending in a line with the stream thereby providing spaces of even distances between said buttresses, and a deck formed integral therewith and provided with a series of rods embedded therein and extending from the bottom of the deck toward the top thereof above said spaces, and a series of cross rods embedded in the deck below said first named rods and between said buttresses, and a series of cross rods embedded in said deck and extending across said buttresses with their ends above said last rods and located above said first rods. 80 85 90

8. A hollow gravity dam embodying buttresses spaced apart from each other and extending in a line with the stream thereby providing spaces of even distances between said buttresses, and a deck formed integral therewith and provided with a series of rods embedded therein and extending from the bottom of the deck toward the top thereof above said spaces, and a series of cross rods embedded in the deck below said first named rods and between said buttresses, and a series of cross rods embedded in said deck and spanning said spaces and extending across said buttresses with their ends above said last rods and located above said first rods. 110

9. A hollow gravity dam embodying buttresses spaced apart from each other and extending in a line with the stream thereby providing spaces of even distances between said buttresses, and a deck supported by said buttresses and provided with a series of rods embedded therein and extending from the bottom of the deck toward the top thereof above said spaces, and a series of cross rods embedded in the deck below said first named rods and between said buttresses, and a series of cross rods embedded in said deck and extending across said buttresses with their ends above said last rods and located above said first rods. 115 120 125

10. A hollow gravity dam embodying out-tresses spaced apart from each other and a deck supported by said buttresses and provided with a series of rods embedded therein and extending from the bottom of the deck 130

toward the top thereof, and a series of cross rods embedded in the deck below said first named rods and between said buttresses, and a series of cross rods embedded in said deck 5 and extending across said buttresses with their ends above said last rods and located above said first rods.

Signed at New York city, in the county of New York and State of New York this 26th day of August A. D. 1910.

CHARLES F. DOEBLER.
